MOVING DISPLAY SIGN

Application filed September 17, 1928. Serial No. 206,562.

This invention relates to improvements in moving display signs.

One object of the invention is to provide a moving sign for displaying certain information, so designed that the information displayed may be readily changed when desired without entirely replacing the information bearing members, thereby greatly reducing the cost of operating the sign.

10 Another object of the invention is to provide a traveling sign of the character indicated, including a plurality of display members exhibited in procession to impart certain information, wherein the order of procession of said members may be changed when desired to impart different information.

A still further object of the invention is to provide a traveling display sign, composed of a plurality of individual display members 20 adapted to be variously assembled to be presented for exhibition in procession in accordance with the order of each assembly, whereby the information imparted thereby may be changed at will.

25 Another specific object of the invention is to provide a device of the character indicated, including individual display members, means for storing said members, the members being arranged in predetermined order 30 in said storage means, means for feeding said members in said predetermined order from the storage means and displaying the same in continuous procession to impart desired information.

35 Another object of the invention is to provide a device for displaying information, including a plurality of individual display members, means for guiding said members in a definite path, storage means for said members, having a receiving end and a delivery

40 end, adapted to contain said members in stacked relation, means for removing said members, one at a time, from the delivery end of the storage receptacle and feeding the same successively in continuous procession along said guide means, thereby visually displaying the same to impart certain information and delivering the same individually through the receiving end of said storage 45 means in the same order as removed there-

from, whereby during the continuous operation of the device the display members are exhibited repeatedly in the same order of procession and the information is thereby also repeatedly displayed as desired.

55 Other and further objects of the invention will more fully and clearly appear from the description and claims hereinafter following.

In the drawings forming a part of this 60 specification, Figure 1 is a detailed perspective view of a device embodying my improved display sign. Figure 2 is a top plan view of the device shown in Figure 1. Figure 3 is a longitudinal vertical sectional view, corresponding substantially to the line 3-3 of Figure 2. Figures 4 and 5 are transverse vertical sectional views, corresponding substantially to the lines 4-4 and 5-5, respectively, of Figure 3. Figure 6 is a horizontal 70 longitudinal sectional view, corresponding substantially to the line 6-6 of Figure 3. Figure 7 is a vertical longitudinal sectional view, corresponding substantially to the line 7-7 of Figure 2. Figures 8 and 9 are vertical 75 transverse sectional views, corresponding respectively to the lines 8-8 and 9-9 of Figure 3. Figure 10 is a horizontal sectional view through the housing, taken on a plane immediately above the motor and driving 80 means shown in Figure 3, illustrating the mechanism at the right-hand end of said figure. And Figure 11 is a vertical sectional view through the bottom portion of the hopper shown at the right-hand end of Figure 85 7, on an enlarged scale, illustrating the holding means for retaining the display plates within the supply hopper.

90 My improved display sign device comprises a housing A, in which the entire display mechanism is contained. The display mechanism within the housing comprises a mirror B; guide members C disposed above the mirror; a supply hopper D; a receiving hopper E; guide members F for guiding the 95 display plates from one hopper to the other; a pair of feed rolls G-G for feeding the display plates continuously along the top guideways; feeding mechanism H for removing the plates from the supply hopper; 100

a lifting mechanism J for feeding the plates to the bottom of the supply hopper; a feeding mechanism K for feeding the plates from the bottom of the receiving hopper to the supply hopper; and driving mechanism for the movable parts, indicated by L, the same including a motor M which is the source of power.

In carrying out my invention, I employ a plurality of individual display members 15, preferably in the form of rectangular plates, and feed the same in continuous procession through an exhibition zone to impart information. The plate-like display members may be formed of any suitable material and carry characters or letters which are reflected onto the mirror of my display sign.

The plate-like members may be formed of metal, such as aluminum, and have the characters or letters stenciled therein, whereby the light rays will pass through the stenciled openings and visibly produce the stenciled letters or characters in the reflecting mirror. The display plates may also be formed of any other desired material, such as celluloid or glass, and the letters, characters or other intelligence-conveying medium defined thereon by suitably opaquequing the plates around the letters, characters or medium so as to permit the light rays to pass through the non-opaque portions and permit proper reflection thereof from the mirror. In displaying the plates, the same are fed in edge to edge contact and, in order to exclude light from passing between the meeting edges of the same, each plate is cut away at opposite sides to provide top and bottom horizontal edge flanges 16 and 17, as most clearly shown in Figures 7 and 11. The flanges 16 and 17 are of such a thickness that when the flange 16 of one plate is overlapped with the flange 17 of the adjacent plate, they form a neat joint and together are of substantially the same thickness as each plate.

The casing A is in the form of a substantially rectangular box, having a removable cover 20, whereby access is obtained to the interior of the housing A. As shown in Figure 3, the cover member 20 is provided with a raised section 21 at the end of the mechanism at which the supply hopper D is located. The raised section of the cover serves the purpose of accommodating certain drive and feed mechanism, hereinafter more fully described. A framework 22 is provided, which carries all of the parts of my improved display sign and the mechanism for operating the same, the framework being removably supported within the housing A.

The framework 22 is directly supported on the bottom of the housing and is provided with a pair of transversely disposed partition walls 23-23, which are spaced inwardly from the opposite ends of the housing A, as most clearly illustrated in Figures 3 and 7.

The walls 23 define the end portions of the display receptacle which contains the mirror B, the latter being suitably secured to the end walls 23 and disposed in angular or inclined position, as most clearly illustrated in Figure 1, so as to reflect the display matter disposed in the zone immediately above the mirror. The front wall of the casing A is provided with a rectangular opening 24 so as to expose the mirror B and the top wall of the housing is preferably provided with a similar rectangular opening 25, corresponding in size to the opening 24 for the purpose of admitting light so as to make the characters, letters or signs, which are carried by the display members or plates, visible. A pair of spaced channel guides 26-26 are secured at the sides of the top of the framework 22 and serve as means for guiding the display members in a straight line path above the mirror B. As shown, the guides 26 extend from the supply hopper D to the receiving hopper E. The top sections of the channel-shaped guide members 26 are cut away immediately above the receptacles D and E, so as to permit removal of the display plates 15 in a vertical direction from the hoppers to allow reassembling of the plates so that they may be displayed in a different order, as hereinafter more clearly pointed out. The two receptacles D and E are of substantially the same design, each having front, rear and side walls which are secured together in any suitable manner, the two receptacles being supported directly from the framework 22.

As most clearly shown in Figure 7, the guide members 26 begin immediately to the left of the receptacle or hopper D and terminate at the inner end wall of the receptacle or hopper E. Both of the receptacles or hoppers D and E are open at the bottom so that the display members may pass freely therethrough.

Spaced guide channels F are employed to guide the display plates from the bottom of the receptacle E to the bottom of the receptacle D, the guide channels being secured to opposite sides of the framework 22 in any suitable manner. As most clearly shown in Figure 7, the lower supporting flanges of the guide channels F extend below the receptacles D and E, so that the opposite ends of the display plates 15 will be supported thereby and held within the receptacles.

The motor M, for driving the parts of my improved device, is mounted on the bottom plate 27 of the framework 22 and is provided with a worm 28 in mesh with a worm wheel 29 mounted on a shaft 30 rotatably journaled in supporting brackets 31-31 secured to the bottom portions of the channel guide members F. At opposite ends, the shaft 30 carries crank discs 32-32, each of which has a link 33 journaled on the crank pin thereof, each link 33 being connected to a rocking

lever arm 34 pivoted between its ends on a shaft 35 having its opposite ends fixed in the framework 22. Each rocking arm 34 has a hub section 36 formed integral therewith and a swinging arm 37 formed integral with the hub. The arms 37 are disposed at opposite sides of the supply hopper D and extend slightly above the same. The upper ends of the arms 37 are curved, as indicated at 38, and are connected by a transversely disposed rod 39.

The rod 39 has a pair of feed pawls 40 pivoted thereon, the pawls 40 being spring pressed downwardly by means of coil springs 41—41 secured at one end to the rod and having the other end bearing on the top of the corresponding pawl 40. The pawls 40 are so disposed that they operate between the two channel guide members C. The feeding means H, which comprises the levers 37 and spring pressed pawls 40, serves to feed one of the plate-like members 15 at a time from the top of the supply hopper D.

The feeding mechanism K for feeding the plate-like members 15 from the bottom of the receiving hopper E, is of similar design to the feeding mechanism H and comprises a pair of pawls 42—42 pivotally mounted on a rod 43 carried by a swinging arm 44, the pawls 42 being yieldingly urged upwardly by means of coil springs 45 mounted on the rod 43 and each having one end secured to the rod and the other end bearing on the bottom side of the corresponding pawl 42. The arms 44 are pivoted on pins 46—46 at opposite sides of the receptacle E, as most clearly shown in Figure 3. The upper ends of the arms 44 are pivotally connected to a pair of links 47—47 which, in turn, are pivotally connected to a pair of rocking levers 48—48 pivoted intermediate their ends on pivot pins 49 extending from braces 50 extending between the end wall 23 of the framework 22 and the adjacent end wall of the receptacle E. The members 48 are connected to the arms 37 by means of links 51—51 which have their opposite ends pivotally connected respectively to these members. As will be evident, upon oscillation of the arms 37, the links 51 will be reciprocated, thereby oscillating the members 48 and, through the connecting links 47, swinging the members 44 to feed the plate-like display members from the bottom of the receiving receptacle or hopper E.

The feeding mechanism for continuously feeding the display members includes the feed rolls G—G, as hereinbefore stated, the same being mounted respectively above and below the channel guides C. The feed rolls G are preferably covered with rubber, as indicated at 52—52, in order to have a gripping action on the surfaces of the display plates. The rolls G are journaled at opposite ends in bearings 53—53 fixed to the guides C. The two rolls are driven in timed relation by in-

termeshing gears 54—54 which are fixed to the journal members at one set of ends of the rolls. As most clearly shown in Figure 5, the journal at the opposite end of the lower roll G carries a sprocket wheel 55 over which is trained a sprocket chain 56 which is driven from a sprocket wheel 57 fixed to the shaft 30.

In order to lift the plates upwardly from the lower guides F and place the same within the supply receptacle or hopper D, the mechanism J is employed. This mechanism includes a lifting table or plate 58 provided with depending lugs 59 at opposite ends thereof, to which are pivotally connected links 60—60 which have their lower ends pivotally connected to the outer ends of the lever arms 34. The table 58 is also swingingly supported on arms 61—61 which are pivoted at their inner ends to the lugs 59 and at their outer ends to lugs 62—62 secured to the framework 22. In order to sustain the stack of plate-like display members 15 within the receptacle or hopper D above the line of feed of the guide members F, retaining spring clips 63—63 are employed, the clips being four in number and disposed in pairs at opposite sides at the front and rear of the hopper or receptacle D. As shown, each of the retaining clips 63 is in the form of a plate-like spring member, having one end secured to the corresponding wall of the receptacle D and having the lower end thereof provided with an inwardly offset section 64 which works through an opening in the side wall and engages underneath the bottom-most plate 15 of the stack.

In the operation of my improved display device, the plate-like display members 15 are arranged in stacks in the two receptacles D and E, the bottommost plate in the receptacle D being supported by the spring clips, as hereinbefore pointed out. The plates are arranged in the receptacles in the order in which it is desired to display the same, so as to give certain information. In displaying the plates, the same are fed continuously through the display zone between the end walls 23 of the display receptacle by means of the continuously rotating feed rolls G—G. When the device is set in operation, the driving motor M causes the shaft 30 to rotate, thereby imparting swinging movement to the levers 37 and 44, thus imparting reciprocating motion to the feed pawls 40 and 42. As shown in Figure 7, the stack of plates in the receptacle D is of such a height that the uppermost plate is in registration with the guideways C. Upon reciprocation of the feed pawl 40, the same will engage within the cut-away edge portion of the uppermost plate member 15 and feed the same forwardly toward the rotating feed rolls G. As this plate is fed forwardly, the feed table or plate 58 will be lifted, thereby raising a plate which has been fed below the supply receptacle

through the bottom thereof, bringing the same into engagement with the bottom of the stack and raising the entire stack so as to bring the plate at the top thereof into registration with the guide members C.

During the next reciprocation of the feed pawl 40, the last named plate will be fed forwardly into engagement with the rear edge of the plate in advance of the same, thereby pushing the last named plate forwardly between the rotating feed rolls G. As will be evident, the plates are thus fed in succession from the top of the supply hopper or receptacle D to the continuously rotating feed rolls G and the latter advance the same in continuous procession between the guide members C through the exhibition zone of the device. The plates push each other along the guide members until the first plate reaches the receptacle E, whereupon the same drops into the receptacle on top of the stack of plates 15 therein. During the time that the plates are intermittently fed from the top of the supply receptacle D, the feed pawl 42 will be operated in timed relation, thereby feeding the plates from the bottom of the receptacle E to the guide members F. The spring pressed pawls 42 of the feed mechanism K are urged upwardly and are thus brought into engagement with the edges of the plates underneath the flanges 16 thereof. The plates, which are fed along the lower guideways F, engage edge to edge and are thus pushed along said guides intermittently, bringing a plate below the hopper or receptacle D each time a plate is removed from the top of said receptacle. As will be evident, the plates which are stored in the two hoppers D and E are thus fed continuously through the device in the same order, the information carried by the same thus being displayed repeatedly. When it is desired to change the information displayed by my improved device, it is merely necessary to remove the cover 20 from the housing A and lift the entire mechanism out of the housing. The plates may then be removed through the tops of the receptacles D and E, and also from the guideways C and F, and reassembled in a different order and replaced within the hoppers and guideways.

The plates which have been removed from the display device may also be replaced by others, a supply of which is kept on hand, to make the necessary changes in order to display the desired information. A certain number of blank plates are also necessary, in order to provide spaces between letters, words and sentences, as will be obvious.

From the preceding description, taken in connection with the drawings, it will be evident that I have provided a display sign device, wherein the same plates having the display means thereon may be repeatedly used in different arrangements to impart various information, thereby greatly economizing in

material, it not being necessary to provide an entirely new display element with the desired information thereon, each time a change is made in the information imparted.

While I have herein shown and described what I consider the preferred manner of carrying out my invention, the same is merely illustrative and I contemplate all changes and modifications which come within the scope of the claims appended hereto.

I claim:

1. In a display sign device, the combination with a housing provided with guideways for guiding individual display plates through an exhibiting zone; of a storage hopper for said plates at each end of said zone; guide means between the bottoms of the hoppers; means for removing plates, one at a time, from the top of one of said hoppers; means for feeding said plates with continuous motion and in procession from said hopper along said guides through the exhibiting zone and depositing the same in the top of the other hopper; and means for feeding the plates from the bottom of one hopper to the bottom of the other hopper along said guides connecting the bottoms of said hoppers.

2. In a display sign device, the combination with a housing provided with guideways for guiding individual display plates through an exhibiting zone; of continuously operating rotary feed rollers for feeding said plates successively and in edge to edge engagement along said guideways through the exhibiting zone; and means for returning said plates in succession to the beginning of said exhibiting zone.

3. In a display sign device, the combination with a supply hopper and a receiving hopper adapted to contain display plates in stacked relation; of guide means between said hoppers for directing said plates through an exhibiting zone; continuously operating feed rollers adjacent said supply hopper for feeding said plates along the guideways continuously in edge to edge engagement and depositing the same in the top of the receiving hopper; means for removing one plate at a time from the top of the stack of the supply hopper and delivering the same to the feed rollers; means for removing the plates, one at a time, from the bottom of said receiving hopper and feeding the same below the said supply hopper; and means for raising the plates, one at a time, to deliver the same to the bottom of said supply hopper.

4. In a display sign device, the combination with a supply hopper and a receiving hopper adapted to contain display plates in stacked relation; of top and bottom guide members connecting said hoppers; yielding retaining means on the supply hopper for sustaining a stack of plates within said hopper; continuously operating means for feeding plates with continuous motion along

the guideways connecting the tops of the hoppers; means for removing one plate at a time from the top of the stack of the supply hopper and delivering the same to the continuously operating feed means; means for

5 removing the plates, one at a time, from the bottom of the receiving hopper and feeding the same below said supply hopper; and means for raising the plates, one at a time, 10 to deliver the same to the bottom of the supply hopper above said yielding retaining means.

5. In a display sign device, the combination with a plurality of individual display 15 plates; of a housing provided with guideways for guiding individual display plates through an exhibiting zone; a reflecting display mirror below said guideways; means for continuously feeding said plates in succession along said guideways through the exhibiting zone; and means for returning said plates in succession to the beginning of said zone.

6. In a display sign device, the combination with a plurality of separate display 25 members having diaphanous and opaque sections; of a reflecting mirror; and means for feeding said display members in procession above the mirror between the same and a 30 source of light exterior to said device.

7. In a display sign device, the combination with a plurality of separate display plates, each plate having a top flange at one edge and a bottom flange at the opposite 35 edge; of means for feeding the plates continuously in endless succession with the top flange of one plate overhanging the bottom flange of the adjacent plate, and displaying the plates in endless procession.

40 8. A display plate having a character thereon, said plate being of rectangular outline and having one end edge cut away to provide a top flange flush with the top surface of the plate and a transverse shoulder below 45 said flange adapted to be engaged by a feeding finger of a feed mechanism and having the opposite end edge cut away to present a bottom flange flush with the bottom surface of the plate and a transverse shoulder above 50 said flange adapted to be engaged by a feeding finger of a feed mechanism.

9. In a display sign device, the combination with a housing having a display zone; of a plurality of units comprising both blanks 5 and those having intelligence-conveying medium thereon, said units being universally interchangeable one with respect to another and interchangeable with others of like character; power-operated means for advancing 10 endlessly, said units through said display zone, progressively, in a predetermined order, the intelligence-conveying portions of said units being non-opaque to thereby permit passage therethrough of light rays from a source outside of said device, and a reflect-

ing mirror disposed adjacent to and on the side of said units remote from the source of light and in operative position with respect to such of said units as are in the display zone.

10. In a display sign device, the combination with a plurality of separate display members adapted to be assembled in varying order of procession; of storage means for said members; means for guiding said members through a display zone; continuously operating feed means for feeding said members with continuous motion through said display zone in endless procession; means for feeding said members from the storage means to the 75 continuous feed means; means for returning said members in the order of said procession to said storage means to be repeatedly fed; and a reflecting mirror below said guide means.

11. In a display sign device, the combination with a plurality of separate display elements having an intelligence-conveying medium thereon; of means for feeding said elements in continuous procession and in horizontal position through an exhibition zone and for returning the same in the order of said procession to be repeatedly fed through said zone in the same order, said means including mechanism for feeding said elements with continuous motion through said zone; and a reflecting mirror in said exhibition zone below said elements for rendering visible the intelligence-conveying medium of said elements.

12. In a display sign device, the combination with a plurality of separate display members each having both diaphanous and opaque sections to thereby provide an intelligence-conveying medium; of a reflecting mirror disposed in an exhibiting zone; storage means from which said members are supplied; mechanism for feeding said members in succession, from said storage means, including means for feeding said elements with continuous motion and in procession through the exhibiting zone, to one side of said reflecting mirror between the latter and a source of light exterior to said display device.

13. In a display sign device, the combination with a plurality of display elements; of means for feeding said elements with continuous motion in succession through an exhibition zone; storage means for said elements at opposite ends of the exhibition zone; means for removing said elements, one at a time, from the storage means at one end of said zone and feeding the same in succession to said continuous feed means, said storage means at the other end of said zone receiving the elements in succession; and feed means for returning the elements in succession from said last named storage means to the other storage means.

14. In a display sign device, the combina-

- tion with a plurality of separate display elements; of guide means for said elements extending through an exhibiting zone; means for storing said elements in stacked relation at opposite ends of said guide means, each storage means having receiving and discharge ends; continuously operating feed means for feeding said elements along said guide means; means for removing said elements, one at a time, from said stack at the discharge end of the storage means at one end of said guide means and feeding the same in succession to said continuously operating feed means, to be fed by the latter in continuous procession through a display zone and to the other storage means; and means for returning said elements, one at a time, from said last named storage means to the receiving end of the other storage means.
15. In a display sign device, the combination with a plurality of individual display members having diaphanous and opaque sections; of a housing; a reflecting display mirror mounted in said housing; guide means for guiding said members past said mirror through a display zone, said guide means being disposed between said mirror and a source of light exterior to the housing; storage hoppers at opposite ends of said display zone for holding said members in stacked relation; and means for feeding said members in succession with continuous motion through said guide means from one hopper to the other.
20. 16. In a display sign device, the combination with a housing provided with guideways for guiding individual display plates through an exhibiting zone; of a storage hopper for said plates at one end of said guide means, from which the plates are fed; a second storage hopper at the other end of said guide means; means for successively removing plates, one at a time, from said first named hopper; means for receiving said plates as removed and feeding the same in edge to edge relation and with continuous motion through said guide means to the second named hopper and depositing the same therein; and means for feeding the plates from said second named hopper to the first named hopper.
25. 17. In a display sign device, the combination with guideways for guiding individual display plates through an exhibiting zone, in horizontal position; of a supply hopper at one end of said zone and a receiving hopper at the other end thereof; means for removing plates, one at a time, from said supply hopper; continuously operating feed means receiving said plates as removed and feeding the same in edge to edge engagement, in continuous procession and with constant motion along said guides through said exhibiting zone and depositing the same in the receiving hopper; and means for removing the

plates from the bottom of the receiving hopper and feeding the same to the bottom of the supply hopper.

In witness that I claim the foregoing I have hereunto subscribed my name this 31st day of August, 1928.

GEORGE J. MEAD.
